COMBINED BOTTLE STOPPER AND POURER

Ernest L. Du Pree, Weston, Conn., and Daniel Goldstein, New York, N. Y., assignors to Schenley Industries, Inc., New York, N. Y., a corporation of Delaware

Application October 5, 1953, Serial No. 27,069

Term of patent 14 years

(Cl. D58—10)

To all whom it may concern:

Be it known that we, Ernest L. Du Pree and Daniel Goldstein, citizens of the United States of America, residing, respectively, at town of Weston, county of Fairfield, and State of Connecticut, and city, county, and State of New York, have invented a new, original, and ornamental Design for a Combined Bottle Stopper and Pourer, of which the following is a specification, reference being had to the accompanying drawing, forming part thereof.

Figure 1 is a side elevational view of a combined bottle stopper and pourer embodying our new design;

Figure 2 is a top plan view thereof; and

Figure 3 is a cross sectional view, taken on the line 3—3 of Figure 1 on an enlarged scale.

The sides not shown are the same as the two sides shown which embody the indentations.

We claim:

The ornamental design for a combined bottle stopper and pourer, as shown and described.

ERNEST L. DU PREE,
DANIEL GOLDSTEIN.
